CLAIM

The ornamental design for a cutting insert as shown and described.

DESCRIPTION

FIG. 1 is a perspective view of our design for a cutting insert;

FIG. 2 is a front view of the cutting insert of FIG. 1;

FIG. 3 is a back view of the cutting insert of FIG. 1;

FIG. 4 is a left view of the cutting insert of FIG. 1;

FIG. 5 is a right view of the cutting insert of FIG. 1;

FIG. 6 is a top view of the cutting insert of FIG. 1;

FIG. 7 is a bottom view of the cutting insert of FIG. 1; and, FIG. 8 is a cross-sectional view taken along section line 8-8 of FIG. 2.

The dash-dash lines in the figures represent portions of the cutting insert that form no part of the claimed design.

1 Claim, 7 Drawing Sheets
